UNITED STATES PATENT OFFICE.

CHESTER A. HOWELL, OF DES MOINES, IOWA, ASSIGNOR OF ONE-THIRD TO J. J. SWIFT,
OF DES MOINES, IOWA.

CONDENSER FOR AUTOMOBILE RADIATORS.

Application filed October 13, 1920. Serial No. 416,729.

To all whom it may concern:

Be it known that I, CHESTER A. HOWELL, a citizen of the United States, and resident of Des Moines, in the county of Polk and 5 State of Iowa, have invented a certain new and useful Condenser for Automobile Radiators, of which the following is a specification.

The object of my invention is to provide 10 a condenser of simple, durable and inexpensive construction, designed to be applied to an automobile radiator instead of the ordinary radiator cap, for the purpose of receiving the vapor arising from the alcohol 15 or other non-freezing solution ordinarily placed in radiators in cold weather, and retaining same therein where it will be subjected to cold air for the purpose of condensing said vapor, and then returning the 20 condensed vapor to the interior of the radiator where it will commingle with the water or the remainder of the liquid therein, to thereby prevent loss by vaporization of the non-freezing solution in automobile radiators. 25

A further object is to provide a device of this character into which the vapors will circulate freely, and in which a maximum of the vapor is exposed to the condensing 30 surfaces of the device, for the purpose of rapidly and efficiently condensing the liquid and returning it to the radiator.

My invention consists in the construction, arrangement and combination of the various 35 parts of the device, whereby the objects contemplated are attained, as hereinafter more fully set forth, pointed out in my claims, and illustrated in the accompanying drawings, in which:

40 Figure 1 shows a perspective view of a radiator having my improved condenser applied thereto.

Figure 2 shows a top or plan view of the condenser, a part being broken away to 45 show the internal construction; and

Figure 3 shows an enlarged detail view, partly in vertical section, illustrating the interior construction of the condenser.

Referring to the accompanying drawings, 50 I have used the reference numeral 10 to indicate an automobile radiator of ordinary construction. These radiators are ordinarily provided at their tops with a screw-threaded cap, which may be removed for filling purposes.

My improved attachment comprises a screw-threaded cap 11, similar to the caps now used on the filling pipes of radiators. In the central portion of this cap is an open-ended tube 12, extended from the top of the 60 cap and to a considerable distance above it. This screw-threaded tube is firmly secured to the cap, preferably by lock nuts 13, above and below the screw cap screwed to the tube.

Mounted on top of the upper lock nut 13, 65 and surrounding the tube 12, is the condenser body portion. This is preferably composed of a series of sheet metal discs, the lower one 14 being fitted around the tube 12 and the upper one 15 being fitted around 70 the collar 16, on which there is a screw cap 17 to provide access to the interior, and through which the radiator may be filled when desired. Between the lower disc 14 and the upper disc 15 is a series of sheet 75 metal discs, with their outer edges connected together by lap joints 18 and their inner edges connected together by lap joints 19, the inner ends being spaced apart from the tube 12 and the discs being arranged, as 80 clearly shown in Figure 3, so that the air may freely circulate between each pair of discs from the outer edges thereof to the inner edges, and on the interior the vapor may freely circulate between the alternate 85 pairs of discs out to the outer edges, thus forming an enclosed chamber for the vapor and a series of passageways between the vapor containing discs through which the atmospheric air may freely circulate. 90

Secured to the upper disc 15, and extending downwardly to a point below the top of the cylinder 12, and between said cylinder and the adjacent lap joints 19, is a vent pipe 20, open at both ends. 95

For the purpose of returning the water of condensation from the condenser back into the radiator, I have provided a tube 21 extended through the tube 12 with its upper end above the bottom of the disc 14 and its 100 lower end extended downwardly far enough to enter the liquid within the radiator.

In practical use the device is readily, quickly and easily applied to any ordinary radiator by removing the radiator cap and 105 placing thereon the condenser, and after it has been thus installed it performs its work automatically without any attention on the part of the operator.

When automobile radiators are exposed 110

to temperatures that will freeze water, it is customary to mix with the water some anti-freezing solution, such, for instance, as alcohol so that the liquid thus mixed will not 5 freeze in such temperatures as are ordinarily encountered. Under these circumstances it is well known that when the automobile engine is in use the liquid will be heated, and when it is heated even to a temperature 10 below the boiling point of water, the alcohol or other non-freezing solution will commence to vaporize. Under these circumstances it frequently happens that the vapor escapes from the radiator and before the operator of the automobile becomes aware of 15 the fact substantially all of the alcohol has passed off in vapor, leaving substantially clear water, which, of course will readily freeze when subjected to low enough 20 temperatures.

By the use of my device and assuming that the radiator has once been filled with a non-freezing solution, say, for instance, fifty per cent alcohol and fifty per cent 25 water, then when the engine becomes heated and the mixture begins to vaporize, the vapor will rise through the tube 12 into the condenser, and as it fills the upper part of the condenser, the air in the condenser being 30 heavier, will descend, and as soon as this is subjected to a slight amount of pressure due to the presence of the vapor the air at the lower part of the condenser will be forced out through the air vent 20, thus permitting 35 the vapor to freely rise within the condenser. The vapor thus formed within the condenser will spread out between the condenser discs, and the atmospheric air will pass through between the discs, thus 40 subjecting the outer surfaces of the sheet metal discs to cold and rapidly moving air, causing rapid condensation on the interior of the condenser, and as this condensation falls to the bottom of the condenser it 45 will escape through the tube 21 to a point below the liquid in the radiator.

In a device of this kind I have found that it is necessary to have a means for the escape of air in order to permit vapor to readily 50 rise within the condenser, as otherwise the vapor would be forced to pass out through the ordinary overflow pipe with which radiators are ordinarily equipped and which could not be plugged when a device of this 55 kind is used. Furthermore, I have found that it is desirable to have the air escape pipe run from a point near the bottom of the condenser body portion and from a

point between the tube 12 and the interior of the condenser, as it is at this point where 60 the cold air accumulates when vapor begins to fill the upper portion.

I claim as my invention:

1. A condenser comprising a tube, means for attaching it to a radiator or the like, a condenser body portion surrounding said tube, and having said tube projected upwardly into its central portion, said body portion comprising a hollow interior designed to contain vapor, and also having its outer surfaces formed in layers to permit the atmospheric air to pass between the layers of the condenser body portion for cooling purposes, and an air vent extending from a point near the bottom of the condenser to a 75 point of discharge, for the purposes stated.

2. A condenser attachment for automobile radiators comprising a hollow body portion, an open-ended tube at the bottom of the hollow body portion and designed to be inserted into a radiator above the water line, a condensation pipe leading from the interior of the body portion through said tube and designed to extend into the radiator below the water line, and an air vent tube leading 80 from the interior of the body portion upwardly to a point of discharge above the body portion, for the purposes stated.

3. A condenser comprising an open-ended tube, a radiator cap through which the tube is extended, means for detachably securing the tube to the cap, a condensation tube supported in the aforesaid tube, and extending downwardly to a point beneath the cap, a condenser body comprising a series of sheet 90 metal discs, the lower one being fitted around the said first mentioned tube, and the upper one being closed at its upper end, and the intermediate ones being open at their central portions, the adjacent intermediate discs being secured together at their outer ends and also at their central portions to form an enclosed compartment in which the vapor contained in the interior may flow outwardly to the outer edges of the space 105 between the discs, and the atmospheric air may flow inwardly between the layers of discs to the place where their inner edges are united, and a vent pipe extending from a point between the first mentioned tube 110 and the interior of the condenser to a point where it will discharge through the top of the condenser, substantially as and for the purposes stated.

Des Moines, Iowa, October 7, 1920.

CHESTER A. HOWELL.
